CLAIM

The ornamental design for a hosel for a golf club head, as shown and described.

DESCRIPTION

FIG. 1 is a perspective view of a hosel for a golf club head showing our new design;

FIG. 2 is a toe end view of the hosel shown in FIG. 1;
FIG. 3 is a heel end view of the hosel shown in FIG. 1;
FIG. 4 is a top plan view of the hosel shown in FIG. 1;
FIG. 5 is a bottom view of the hosel shown in FIG. 1;
FIG. 6 is a front elevational view of the hosel shown in FIG. 1; and,

FIG. 7 is a rear elevational view of the hosel shown in FIG. 1;

The broken lines in FIGS. 1-7 are for illustrative purposes only and form no part of the claimed design.
